ABSTRACT: 1. A vehicle adapted to translate in proximity to the earth's surface having in combination:

- a. a faired streamlined body having a leading edge and a trailing edge, and being disposed about a cambered mean line extending from said leading edge to said trailing edge, the bottom of said body having a slope in said leading edge not exceeding 10° and forming a diffuser section to provide a pressure difference between upper and lower surface of said body during translation of said body thereby producing aerodynamic lift;
- b. means along the sides of said body and defining two downwardly directed slots to produce downwardly directed jets; and
- c. means for delivering air to said slot defining means both during hovering and translation, to discharge air through said slots thereby producing downwardly extending air jet curtains at the sides of said body and of said diffuser section permitting lift producing flow into said diffuser section from said leading edge and to be discharged from underneath said trailing edge.

GROUND EFFECT MACHINE

This is a continuation application of my application, Ser. No. 440,665, filed Mar. 1, 1965, which, in turn, is a continuation in part application of my application, Ser. No. 839,870, filed Sept. 14, 1959. The matter added to the application Ser. No. 440,665 having been canceled from this specification. U.S. Pat. applications Ser. Nos. 440,665 and 839,870 have been abandoned.

The invention of this application pertains to improvements in ground effect machines and in particular relates to an improved ground effect machine which is shaped to provide a diffuser channel on its underside to develop a sustaining pressure therein from the forward motion of the machine, and which utilizes a single power flow of air to provide both propulsion and a screen for the high pressure diffuser channel flow.

An object may be sustained against the force of gravity in a number of ways now known to man, as follows:

1. Centrifugal force. Examples are the satellites which have been placed in orbit about the earth.
2. Buoyancy. Examples are lighter-than-air machines, balloons, and boats.
3. Imparting downward momentum. Conventional aircraft, helicopters, and hydrofoils obtain a lift force as a reaction to their imparting downward momentum to the fluid in which they are sustained or through which they are moved. This reaction force is the commonly accepted conventional three dimensional aerodynamic lift, which normally leaves residual dissipative energy in the air.
4. Internal Stress. The most common example is any structural support, such as a chair or table leg. A pneumatic tire which contains air under pressure is another example. In this case the air in the tire sustains the compression stress, the pressurized air being contained by tension in the tire wall. In a conventional Ground Effect Machine a volume of air under the machine similarly sustains the compression stress caused by the weight of the machine, the pressurized air in this case being contained by a screen or jet of air emitted around the entire periphery. This peripheral curtain of air is forced outward by the ground, and the resulting centrifugal force in the curtain is balanced by a pressure which is built up and sustained in the air bubble underneath the machine.

An infinite span wing in motion through the air similarly develops a pressure stress in the surrounding air, which produces a two-dimensional aerodynamic lift force as a reaction to the development of downward momentum, but without leaving any residual dissipative energy in the air.

Ground Effect Machines are essentially examples of category 4 above, in utilizing the internal stress that may be developed between the machine and the ground. This force may be developed with no expenditure of energy, other than that in the curtain of air itself, and this fact is the advantage obtained by operating the machine in ground proximity.

Conventional Ground Effect Machines thus obtain their lift as the internal stress developed in the underside pressure bubble through the centrifugal force of a peripheral jet sealing curtain. In hovering the pressure bubble is essentially static underneath the machine. In translation the pressure bubble is essentially carried with the machine as it moves, the curtain jet being deflected aft to provide propulsion, and the front curtain if desired reduced because of the dynamic pressure provided by stagnation of the oncoming stream against the front of the pressure bubble as it is moved with the machine. Auxiliary propulsion if desired may be provided by external propellers or jet engines.

The present invention provides a fundamental improvement over such conventional Ground Effect Machines by a unique arrangement whereby in translation the sustaining force for the machine is developed as an internal stress, not in a pressure bubble carried with the machine, but in an unpowered flow of air under the machine due to the forward motion of the device itself. In this improved machine its shape and particularly the effective shape of its underside is configured to pro-

vide a channel for the air to flow, bounded on the top by the machine, on the bottom by the ground, and on the two sides by the pneumatic curtain.

In the translation regime the front and rear curtains are turned off so that air can flow through the channel unobstructed. The machine is then provided with an effective concave shape of its underside, as determined by both the contouring and camberline of the body, so that the dynamic pressure of the air flow under the machine is converted to a static pressure higher than that on the upper side, and in general higher than atmospheric, thus providing the internal stress between the machine and the ground which appears as an upward or lifting force to balance the force of gravity.

Thus the present invention provides a two-phase machine. In the hovering (or slow translation) phase the machine utilizes an annular jet completely around the periphery, sealing the pressure bubble under the machine, and dragging this pressure bubble along with it in slow translation. It should be noted that the annular jet completely around the periphery is not a requirement for this invention. For the hovering (or slow translation) phase any part of the periphery, for example the front and rear, can be sealed by flaps, skegs, or fences of any type, but pneumatic curtains are described here merely to demonstrate compatibility with the high speed channel flow regime and to illustrate an operable vehicle.

In the high speed translation phase, the front and rear curtains are turned off, and the pressure bubble is discarded. The external unpowered air is then allowed to flow unobstructed through the underside channel provided by the side jets. The fans on board the machine then deliver air only to the side curtains. The internal stress or pressure in the air flowing through the channel in this case developed by the effective shaping of the underside, both by contouring of the underside and/or curvature of the mean body line of the machine (as well as by the other elements of the channel such as the ground and side jets if applicable), and the side jets simply seal this pressure, at the same time providing propulsion by being inclined aft.

This two-phase improved Ground Effect Machine combines (1) all the advantages of conventional Ground Effect Machines in hovering with (2) greatly improved translational efficiency due to the development of an internal stress in an unrestricted flow of air under the machine, thereby overcoming the force of gravity without the requirement of dragging along the sustaining pressure bubble.

In both these operational phases the sustaining force is the internal stress. No residual downward momentum is required to be imparted to the air as in conventional three-dimensional aerodynamic lift, and there is no corresponding dissipative energy required as in conventional reduced drag. Energy is required to provide the sealing curtain in both operational phases. In translation additional energy is required to overcome profile drag, but no energy is required to develop the lift force itself as in a conventional aircraft.

The body of this improved machine of the present invention is thus faired or streamlined in a vertical section on both the upper and underside in the direction of motion, and provided with a fairly sharp although locally rounded leading edge, and a sharp trailing edge as in a conventional wing. This streamlined body is then superimposed on a cambered mean line, thus producing a body shape having an effective camber or concave curvature to its underside, which together with its side air curtains provides in conjunction with the ground or water surface a channel for the air flow under the body in such a manner as to provide a lifting force. In this application, such a body is referred to as a channel flow lifting body. This body thus provides a channel in the streamwise direction to provide first, a diffuser to slow down and increase the static pressure of the air; second to provide a plenum chamber to maintain this higher pressure under as long a region of the machine as possible; and third, a contraction region to accelerate the air back to its initial velocity to minimize drag.

These three functional elements of the channel may be provided in any one of several ways and yet still accomplish the

basic diffusion required. For example, the second element, the plenum chamber, may be reduced in size until completely omitted, the channel then consisting solely of a diffuser section forward, continuing directly into the contraction section aft. On the other hand, the first element, the diffuser section may be simply reduced in length until finally omitted altogether, in which case the diffusion will take place externally in front of the machine. Likewise, the last element, the contraction section, may be also reduced in length until finally omitted altogether, in which case the contraction will take place externally aft of the machine. Or both the diffusion and contraction sections may be accomplished externally forward and aft of the machine respectively, and the bottom of the machine itself thus entirely devoted to the plenum region, and in this case the bottom of the machine may be flat, the effective concavity then being provided by the mean line of the body itself.

All of these secondary variations nevertheless are subordinate to the primary feature of a mean camber line which is concave down, thus providing an effective concavity to the body and its underside smoothly from the leading edge to the trailing edge of the body, thereby providing aerodynamic lift.

The mass of air flowing through such a diffuser channel must be conserved and hence for incompressible flow the product of the channel cross-sectional area A and the axial velocity V must be constant, where the subscript 1 refers to any arbitrary cross section, and where the subscript 2 refers to any different cross section, i.e.:

$$A_1 V_1 = A_2 V_2$$

Thus, as the channel expands, i.e., as its cross-sectional area increases, the axial velocity will decrease. But energy must also be conserved in the flow, and so, as the velocity V decreases, the static pressure p will increase in accordance with Bernoulli's equation, where ρ is the density of the fluid, i.e.:

$$p + \frac{1}{2} \rho V^2 = \text{constant}$$

This higher static pressure in the channel on the underside of the machine, as compared to the atmospheric or lower pressure on its upper surface, provides a force to sustain the machine above the surface of the ground when in forward motion.

Also, in accordance with the present invention, the edges of the under surface of the above described body are bounded by a slot through which a jet is emitted down, thus providing a pneumatic extension of the sides of the flow channel all the way to the ground, and screening the high pressure air developed therein.

This slot is provided around the entire periphery of the machine, that is, across the entire front and rear of the underside of the above described body. However, the sections across the front and rear of the body are used only when the machine is hovering, as in such cases the jet is required around the entire periphery of the machine.

Thus when the machine is hovering, the jet is emitted around the entire periphery, and is aimed down and inward to provide the greatest curvature of the jet and hence the highest pressure on the underside of the machine that may be developed by the centrifugal force of the jet as it is forced to flow outward. The machine may then be moved at moderate speeds in any direction by suitable deflection of the jet.

For high speed forward translation, the jet is gradually deflected aft, providing propulsion. The jet emitted from the sections of the slot across the front and rear of the machine are at the same time gradually shut off, the jet then being emitted only along the sides of the flow channel. The sustaining pressure is then gradually developed by the forward motion as described above, the jet along the sides screening the high pressure air developed in the channel. The flow channel is then bounded on the top by the machine body, shaped to provide an underside diffuser as described, on the sides by

jet screen, and on the bottom by the ground or water. The channel aperture at the front of the machine is determined by the height of the machine above the ground, and the width between the side jet slots provided. The channel aperture at

5 the rear of the machine is similarly determined by the machine height above the ground, and the width provided by the side jets in defining the contraction section. The complete flow perturbation involved in the development of the lift force underneath the machine, however, may extend both forward and 10 aft of the machine body itself.

In this specification a pressure bubble is defined as a mass of pressurized air which is stationary with respect to the vehicle, and thus is dragged along with the vehicle when it moves, and 15 which with respect to the ground then moves as does the vehicle. On the other hand, the channel flow as described in this specification is not stationary with respect to the vehicle, but is flowing under the vehicle. With respect to the ground, however, the channel flow air is stationary, and the vehicle moves over it.

20 An advantage of this novel improved ground effect machine is that at high speeds it does not have to drag its sustaining bubble along with it, but instead generates a high pressure in the air that it passes over in its channel. This latter mode of 25 operation will require much less power than modes of operation which drag a sustaining pressure bubble along with the machine.

Thus this invention provides a channel shaped, pressure sustained ground effect machine which will require considerably less power in translation motion as compared with conventional annular jet machines.

The foregoing and other readily apparent features of my present invention will be better understood by reference to the 30 following more detailed specification and accompanying drawings, in which:

FIG. 1 is a perspective view of the preferred embodiment of a ground effect machine embodying the features of the present invention, and showing the machine sustained above water, either hovering or in forward motion;

40 FIG. 2 is an underside perspective view of the ground effect machine of FIG. 1, illustrated as seen from under the water surface;

FIG. 3 is a plan view of the machine of FIG. 1;

45 FIG. 4 is a side view of the machine of FIG. 1;

FIG. 5 is a front view of the machine of FIG. 1;

FIG. 6 is a sectional view taken along the line 6-6 of FIG. 3, 50 illustrating the inward and downward inclination of the jet to provide the pressure screen, both in hovering and in forward translation motion; and

FIG. 7 is a sectional view taken along the line 7-7 of FIG. 3, 55 illustrating the aft inclination of the jet employed to provide propulsion for forward motion.

In the drawings, like numerals refer to like or corresponding parts throughout the several views.

Referring to FIG. 1, there is illustrated a ground effect machine constructed in accordance with the present invention comprising a main body, hull, or chassis 20. As illustrated in FIG. 2, this body 20 has on its underside a pressure generating 60 flow channel 21 having a forward diffuser section 23, a center plenum chamber 24, and an aft contraction section 25. The body 20 has a leading edge 33 and trailing edge 34.

The diffuser section 23 is normally limited in its expansion geometry to walls of not more than 10° slope to prevent 65 separation of the air flow.

As illustrated in the side elevation of FIG. 4, the body 20 has a cambered mean line 22, with a faired and streamlined thickness distribution above and below this line. This body shape, in the proximity of the ground, causes the air flow to diffuse forward and to contract aft of the machine, such that 70 the stagnation streamline of the air flow forms a continuation of the cambered mean line 22 forward and aft of the body 20 itself.

This extended stagnation streamline 22f forward and 22a aft of the machine extends and bounds the flow channel 21 for-

ward and aft of the machine itself, such that the forward diffuser region 23' extends in part at least forward of the body 20, and the aft contracting region 25' extends in part at least aft of the body 20.

FIG. 3 further illustrates in a plan view the air flow in the channel 21 forward and aft of the body 20, illustrating in particular the curved streamlines in the air flow of diffusion in the forward diffuser region 23' and of contraction in the aft contracting region 25'.

The entire periphery of the machine 20 is bounded by a slot 27 from which is emitted a jet 28. The air for this jet is taken on board the machine through one or more scoops 29, induced by means such as the air flow device 30, viz. an engine fan combination or a jet engine, which pumps the air through a duct or chamber 31 to the slot 27, from which the air emerges as the jet 28.

The jet 28 is emitted from the slot 27 around the entire periphery down and inward towards the center of the machine 20, as illustrated in FIG. 6, for hovering. For forward motion, the jet 28 is then emitted from the sections of the slot 27 along the sides only, and is deflected aft by pivotable louvers 32, the jet still having a downward component to screen the sustaining pressure developed in the channel 21 by the forward motion, as illustrated in FIG. 7. Means (not shown) may be provided to dispose the louvers 32 in such attitude as will provide the proper direction of the jet 28 for any operation condition.

While the preferred form and method of employing the invention have been described and illustrated, it is to be understood that the invention lends itself to numerous other embodiments without departing from its basic principles.

I claim:

1. A vehicle adapted to translate in proximity to the earth's surface having in combination:

a. a faired streamlined body having a leading edge and a trailing edge, and being disposed about a cambered mean line extending from said leading edge to said trailing edge, the bottom of said body having a slope in said leading edge not exceeding 10° and forming a diffuser section to provide a pressure difference between upper and lower surface of said body during translation of said body thereby producing aerodynamic lift;

b. means along the sides of said body and defining two downwardly directed slots to produce downwardly directed jets; and

c. means for delivering air to said slot defining means both during hovering and translation, to discharge air through said slots thereby producing downwardly extending air jet curtains at the sides of said body and of said diffuser section permitting lift producing flow into said diffuser section from said leading edge and to be discharged from underneath said trailing edge.

2. In the ground effect machine adapted to translate in proximity to the earth's surface, the combination of:

a. a faired streamlined body having a leading edge, a trailing edge, and sides and being disposed about a cambered mean line extending from said leading edge to said trailing edge, the bottom of said body having a slope in said leading edge not exceeding 10° and forming a diffuser section, said body further having jet producing means including a slot extending around the lower periphery of said body, said slot being directed downwardly and inwardly;

b. means for delivering air to said jet producing means both during hovering and translation;

c. closure means to inhibit air discharge through the portion of the slot which extends along the underside of said leading edge and said trailing edge of said body;

d. means for operating said closure means to close off said portions of said slot whereby the unpowered air stream to which the body may be subjected when translating relative to the earth's surface may develop sustaining pressures in combination with said body to provide aerodynamic lift; and

e. thrust control means being disposed in each portion of the slot which extends along a side of said body, and said thrust control means being directable to vary the direction of the air so emitted through said portion of the slot to any fore and aft degree whereby a reaction force in either direction may be imparted to either or both sides of the body.

3. In a ground effect machine adapted to translate in proximity to the earth's surface, the combination of:

a. a faired streamlined body having a leading edge and a trailing edge, and being disposed about a cambered mean line extending from said leading edge to said trailing edge, the bottom of said body having a slope in said leading edge not exceeding 10° and forming a diffuser section, said body further having jet producing means including a slot extending around at least portions of its lower periphery of said body, said slot being directed downwardly and inwardly;

b. means including duct for delivering air to said jet producing means both during hovering and translation;

c. closure means governing the portions of the slot which extend along the underside of said leading edge and said trailing edge of said body;

d. means for operating said closure means to close off said portions of said slot, whereby the ambient air stream to which the body may be subjected when translating relative to the earth's surface may develop sustaining pressures in combination with said body to provide aerodynamic lift; and

e. thrust producing means provided in said ground effect machine for producing translation.

4. A vehicle adapted to translate in proximity to the earth's surface having in combination:

a. a faired streamlined body having a leading edge and a trailing edge, and being disposed about a cambered mean line extending from said leading edge to said trailing edge, the bottom of said body having a slope in said leading edge not exceeding 10° and forming a diffuser section, said body further having jet producing means including a slot extending around at least portions of its lower periphery of said body, said slot being directed downwardly and inwardly;

b. means for delivering air solely to said jet producing means both during hovering and translation;

c. closure means being disposed in the slot portions which extend along the underside of said leading edge and said trailing edge of said body;

d. means for operating said closure means to close said slot portions during translation whereby the exterior air flow to which the body may be subjected when translating relative to the earth's surface may in combination with said body provide aerodynamic lift; and

e. thrust producing means provided in said vehicle for producing translation.

5. In a ground effect machine adapted to translate in proximity to the earth's surface, the combination of:

a. a faired streamlined body, having a leading edge, a trailing edge, and sides being disposed about a cambered mean line concave down extending from said leading edge to said trailing edge, the bottom of said body having a slope in said leading edge not exceeding 10° and forming a diffuser section, said body further having jet producing means including a slot extending around the lower periphery of said body, said slot being directed downwardly and inwardly;

b. means for delivering air solely to said jet producing means both during hovering and translation;

c. first vane means, said first vane means being disposed in the portion of the slot at said leading edge and at said trailing edge of said body;

d. means for operating said first vane means to close the slot portions at said leading and trailing edges whereby the free stream air to which the body may be relatively sub-

jected when translating relative to the earth's surface may develop sustaining pressures in combination with said body to provide aerodynamic lift consisting of a lower pressure region on the upper surface of said body and a higher pressure region on the lower surface of said body, said sustaining pressure regions being isolated from each other by side air curtains produced by discharge of air through slot portions at said sides; and

e. second vane means, said second vane means being disposed in each portion of the slot which extends along a side of said body, and said second vane means being directable to vary the direction of the air so emitted through said portion of the slot to any fore and aft degree, whereby a reaction force in either direction of a preselected degree may be imparted to either or both sides of the body by a particular disposition of the direction of the said second vane means in said portion of the slot.

6. In a ground effect machine adapted to translate in proximity to the earth's surface, the combination of

a. a faired streamlined body having a leading edge, a trailing edge, and sides and being disposed about a cambered mean line extending from said leading edge to said trailing edge, the bottom of said body having a slope in said leading edge not exceeding 10° and forming a diffuser section, said body further having jet producing means including a slot extending around the lower periphery of said body, said slot being directed downwardly and inwardly;

b. means for delivering air solely to said jet producing means both during hovering and translation;

c. closure means disposed in the portion of the slot which extends along the underside of said leading edge and said trailing edge of said body;

d. means for operating said closure means to close off said portions of said slot whereby the unpowered air stream to which the body may be subjected when translating relative to the earth's surface may develop sustaining pressures in combination with said body to provide aerodynamic lift; and

e. thrust control means being disposed in each portion of the slot which extends along a side of said body, and said thrust control means being directable to vary the direction of the air so emitted through said portion of the slot to any fore and aft degree whereby a reaction force in either direction may be imparted to either or both sides of the body.

7. In a ground effect machine adapted to translate in proximity to the earth's surface, the combination of:

a. a faired streamlined body having a leading edge and a trailing edge, and being disposed about a cambered mean line extending from said leading edge to said trailing edge, the bottom of said body having a slope in said leading edge not exceeding 10° and forming a diffuser section, said body further having jet producing means including a slot extending around at least portions of the lower periphery of said body, said slot being directed downwardly and inwardly;

b. means for delivering air solely to said jet producing means both during hovering and translation;

c. closure means disposed in each portion of the slot which extends along the underside of said leading edge and said trailing edge of said body;

d. means for operating said closure means to close off said portions of said slot, whereby the ambient air stream to which the body may be subjected when translating relative to the earth's surface may develop sustaining pres-

sures in combination with said body to provide aerodynamic lift; and

e. thrust producing means provided in said ground effect machine for producing translation.

8. In a ground effect machine adapted to translate in proximity to the earth's surface, the combination of:

a. a faired streamlined body having a leading edge, a trailing edge, and sides being disposed about a mean line being at least partially cambered concave down and extending from said leading edge to said trailing edge, the bottom of said body having a slope in said leading edge not exceeding 10° and forming a diffuser section, said body further having jet producing means including a slot extending around the lower periphery of said body, said slot being directed downwardly and inwardly;

b. means for delivering air to said jet producing means both during hovering and translation;

c. first vane means, said first vane means being disposed in the portion of the slot at said leading edge and at said trailing edge of said body;

d. means for operating said first vane means to close the slot portions at said leading and trailing edges whereby the free stream air to which the body may be relatively subjected when translating relative to the earth's surface may develop sustaining pressures in combination with said body to provide aerodynamic lift consisting of a lower pressure region on the upper surface of said body and a higher pressure region on the lower surface of said body, said sustaining pressure regions being isolated from each other by side air curtains produced by discharge of air through slot portions at said sides; and

e. second vane means, said second vane means being disposed in each portion of the slot which extends along a side of said body, and said second vane means being directable to vary the direction of the air so emitted through said portion of the slot to any fore and aft degree, whereby a reaction force in either direction of a preselected degree may be imparted to either or both sides of the body by a particular disposition of the direction of the said second vane means in said portion of the slot.

9. A vehicle adapted to translate in proximity to the earth's surface having in combination:

a. a faired streamlined body having a leading edge and a trailing edge, and being disposed about a mean line extending from said leading edge to said trailing edge, said mean line being cambered concave down along at least a part of its length, the bottom of said body having a slope in said leading edge not exceeding 10° and forming a diffuser section, said body further having jet producing means including a slot extending around at least portions of the lower periphery of said body, and said slot being directed downwardly and inwardly;

b. means for delivering air to said jet producing means both during hovering and translation;

c. closure means to inhibit air discharge through each portion of the slot which extends along the underside of said leading edge and said trailing edge of said body;

d. means for operating said closure means to close off said portions of said slot, whereby the ambient air stream to which the body may be subjected when translating relative to the earth's surface may develop sustaining pressures in combination with said body to provide aerodynamic lift; and

e. thrust producing means provided in said vehicle for producing translation.
